STEPHEN D. SARGEANT, OF CHARLESTON, SOUTH CAROLINA, ASSIGNOR OF TWO-THIRDS TO JOHN F. RILEY, OF CHARLESTON, SOUTH CAROLINA.

TUBE-CLEANER.

1,022,974.

Specification of Letters Patent.

Patented Apr. 9, 1912.

Application filed February 23, 1911. Serial No. 610,426.

To all whom it may concern:

Be it known that I, STEPHEN D. SARGEANT, a citizen of the United States, and a resident of Charleston, in the county of 5 Charleston and State of South Carolina, have made certain new and useful Improvements in Tube-Cleaners, of which the following is a specification.

My invention relates to improvements in 10 tube cleaners, especially those tubes used in locomotive boilers, and it consists in the combinations, constructions, and arrangements herein described and claimed.

An object of my invention is to provide 15 a device which will render it unnecessary to take out the brick arches for cleaning the tubes, which arches have to be replaced subsequent to the cleaning operation.

A further object of my invention is to 20 provide a cleaner which may be operated by one hand, and in which a valve for admitting or cutting off compressed air may be manipulated by mere pressure of the fingers of the hand which holds the device without 25 shifting the position of the hand.

A further object of my invention is to provide a flue cleaner capable of immediate use on tubes of varying size without any need of adjusting the parts of the cleaner.

30 Other objects and advantages will appear in the following specification, and the novel features of the device will be particularly pointed out in the appended claims.

35 My invention is illustrated in the accompanying drawings forming part of this application in which—

Figure 1 is a side view showing one embodiment of my invention, and Fig. 2 is an 40 enlarged central longitudinal section of the device showing its application to a tube.

Referring now particularly to Fig. 2, I have shown therein a hollow rod A, which is threaded at one end as shown at B, and 45 which is closed at the opposite end with the extension of the small air openings C. Near these openings is an annular flange D. The threaded end B of the tube or hollow rod A is provided with a tapered valve seat E arranged to receive the end of a valve F. This valve is disposed in a valve casing G, which is threaded internally to fit the threaded end B of the tube A. The casing G has a lateral extension H which is bent 50 in the form of a curve as shown in the draw-

ings, and which constitutes a handle for manipulating the device as well as an inlet tube for the compressed air. In order to attain this latter object, the handle is provided with a passage h and the end of the handle is provided with a threaded opening h² in which the end of a flexible hose K may be secured. The valve casing G is provided with a cylindrical bore g in which the valve F is arranged to slide, the valve being held 60 normally against its seat E by means of a spiral spring L. The valve stem f² extends through an opening in the end of the valve casing and bears at its end a gripping member M. This grip member is curved, as 65 shown in the drawings, and is arranged to extend into a recess h³ on the inner side of the handle H. Arranged to slide on the tube A is a tapered plug P having a recess p in its larger end arranged to receive the 70 end of a spiral spring S, which surrounds the tube A, and which bears upon the plug at one end, and upon the end of the valve casing G at the other.

From the foregoing description of the 75 various parts of the device, the operation thereof may be readily understood. When it is desired to clean the tubes, the hose K is adjusted to the device in the manner shown in Fig. 1 and the opposite end is 80 connected with a supply of compressed air (not shown). The spring L, as stated, normally holds the valve F, so as to shut off communication between the interior of the handle H and the interior a of the tube A. The plug P is placed in the open end of a tube such as that shown at T in Fig. 2, and 85 is pushed in as far as it will go. The plug effectually closes the end of the tube. The fingers now close upon the grip member M, thereby opening the valve F, and permitting the compressed air to enter the hollow tube A, as shown by the arrows in Fig. 2. Further pressure of the handle inwardly will 90 compress the spring S but will permit the delivery end of the tube A to pass farther into the large tube T, so that the air may be delivered through the opening C at various points. If the next set of tubes to be 95 cleaned are larger than the first set, it is only necessary to push the tapered plug P until it closes the opening of the tube to be cleaned when the same operation is repeated.

The device is of comparatively light 100

weight, and may be made of metal such as iron or brass. It will be noted that compressed air is used, and, therefore the handle can serve as an inlet member for admitting the air into the tube A. The use of compressed air, of course, would not heat the handle. This is an important feature of this device. Where steam is used the handle cannot serve as the inlet member without the provision of some nonconducting material. In my device, I do away with the necessity of nonconducting material, while at the same time providing a tool which is more compact in that it has few parts. It can also be more readily manipulated than if it were provided with a handle, and also an auxiliary inlet tube.

I claim:—

1. In a tube cleaner, a hollow rod threaded at one end and provided with delivery openings at the other end, a handle for said rod, said hollow handle having a bore arranged to receive the threaded end of said hollow rod, a valve disposed in said bore and arranged to close the end of said hollow rod,

a tapered plug loosely mounted on said hollow rod, and a grip member disposed adjacent the grip portion of said handle for operating said valve.

2. In a flue cleaner, a hollow rod threaded at one end and provided with delivery openings at the other end, a hollow handle provided with a bore arranged to receive said hollow rod, said hollow handle being curved to provide a grip portion and having a recess, a valve disposed in the bore of said handle, a spring for normally holding said valve against the end of said hollow rod, a valve stem, a gripping member carried by said valve stem and arranged to extend into the recess in said hollow handle, a tapered plug loosely disposed on said hollow rod and provided with a recess in its larger end, and a coiled spring disposed on said hollow rod and arranged to bear at one end on said handle and at the other on said plug.

STEPHEN D. SARGEANT.
